FLOWERPOT SAUCER

Irving H. Greene, New York, N. Y.

Application December 10, 1938, Serial No. 244,931

8 Claims. (Cl. 47—38)

The invention relates to an article of manufacture constituting a saucer or tray suitable for use as a base for flowerpots. The saucer or tray, in accordance with the preferred embodiment of my invention, is fabricated of molded rubber, although the features of novelty embodied in my construction of flowerpot saucer or tray are equally capable of embodiment in like articles fabricated of other materials, for instance ceramic, 5 clay, china, etc.

One of the objects of the invention is to provide a base, such as a saucer or tray, for a flowerpot of the conventional type containing flowers and plants in the home, garden, etc., in which 10 the novel construction involving the use of a sunken bottom, pitched towards the center of the saucer, is attained by the provision of a plurality of ribs of particular disposition and configuration on both the inner and outer surfaces 15 of the bottom of the saucer or tray.

A further object of the invention is to provide a saucer or tray, embodying these novel features, with a centrally located pad of moisture-absorbing material, such as felt, which is capable of 20 transmitting the water collected in the center of the sunken bottom of the saucer or tray, to the soil in the flowerpot through the conventionally provided opening in the bottom of the flowerpot, so as to promote a healthy plant growth. A reservoir of moisture is thus provided which is effective to keep the plant alive and to impart thereto a beauty otherwise capable of securement only by careful attendance upon the plant and the fixed periodical replenishing of water necessary to promote its growth and healthy and 25 attractive appearance.

In accordance with my invention, I provide a saucer or tray, which is to constitute the base for a flowerpot, with a plurality of nearly, but not 30 quite, radially extending ribs upon the bottom surface of the tray, which ribs increase in vertical thickness from the center of the tray toward its outer peripheral edge. Upon the interior surface of the bottom of the saucer or tray, and 35 substantially above the elongated ribs provided along the bottom surface thereof, I provide a plurality of smaller ribs extending at angles to the larger ribs, which smaller ribs decrease successively in vertical thickness from their ends 40 nearer the center of the saucer or tray toward the ends nearer the peripheral edge of the tray. In this manner, the base portion of the saucer or tray is given a sunken character, with a pitch 45 extending from the outer peripheral edge of the saucer or tray, towards its center. At the same 50

time, by reason of the increased thickness of the smaller ribs towards the center of the tray, a substantially plane surface is provided by the upper surfaces of such small ribs to support the flowerpot in proper vertical position, within the 55 saucer or tray.

In accordance with my invention, I provide, at the center of the tray a substantially circular pad of absorbent material, for instance felt, which thus is positioned immediately below the 10 conventional opening in the center of the bottom of the flowerpot, the absorbent pad constituting a reservoir for water collected at the center of the saucer or tray by reason of the pitched character of the tray bottom, and is effective to deliver such water, through the aperture in the flowerpot, to the soil contained in such flowerpot.

A specific embodiment of my invention is illustrated in the accompanying drawing, in which Fig. 1 is a vertical section through a flowerpot 20 saucer or tray, in the construction of which my invention has been embodied, the vertical section being taken along the line 1—1 of Fig. 2; Fig. 2 is a plan view of the saucer; and Fig. 3 is a bottom view thereof.

Referring more particularly to the drawing, in which similar reference characters identify similar parts in the several views, 4 is the body of the saucer, which, in the preferred embodiment illustrated, is formed of molded rubber, the upper peripheral edge thereof being provided with a circumferential bead 5. The bottom 6 of the saucer or tray has imparted thereto a definite pitch, the degree of which is determined by the provision, upon the lower surface thereof, of a 30 plurality of elongated ribs 7, integrally formed with the tray, which ribs extend along the bottom surface of the tray from points somewhat removed from the center of the tray towards, and near, the peripheral edge of the bottom. In the 40 particular embodiment of my invention illustrated, I have provided six of such elongated ribs, which are not exactly radial, as shown clearly in Fig. 3, but somewhat offset, the axes of the ribs, if extended toward the center of the tray, passing to just one side of the exact center thereof.

Each of the ribs 7 tapers in thickness from its outer end near the periphery of the tray bottom, toward the center, as shown clearly in Fig. 1. This tapering in the vertical thickness of the 50 ribs produces a sunken bottom with a pitch thereof which depends upon such degree of tapering in thickness of the elongated ribs.

Upon the opposite or inner face of the base of the saucer, and substantially above the elongated

gated ribs 7, I provide an equivalent number of groups of short ribs 8, 9 and 10, the ribs increasing in length from the center of the saucer towards its peripheral edge, and therefore from the inner ends of the underlying elongated ribs 7 toward the outer ends thereof. The ribs 8, 9 and 10, as clearly shown in Fig. 2, are preferably disposed at a substantial angle to the axis of the underlying elongated rib.

10 In order to secure a substantially plane flat surface for supporting the bottom of the flowerpot, the short ribs 8, 9, and 10 are successively tapered in vertical thickness from their ends nearer the center of the saucer toward their outer ends, as shown clearly in Fig. 1. This tapering in vertical thickness accomplishes the further purpose of providing in substantially the center of the sunken bottom of the saucer or tray sufficient vertical space to accommodate a preferably disc-shaped pad 11 of absorbent material such as felt, the disc being preferably substantially of the same size or slightly larger than the conventional aperture provided in the bottom of the flowerpot, the outer contour of which is shown 25 in dotted lines at 12 in Fig. 1.

From the above description, it will be noted that I have provided a novel flowerpot saucer or tray which has distinct advantages over prior art structures. These advantages may be summarized as constituted by the provision of a sunken bottom for the saucer, which permits the accumulation of a sufficient amount of water in the center to keep the soil in the flowerpot moist to the degree necessary; the provision of the absorbent pad constituting a reservoir, at the center of the tray, the pad acting as a wick, delivering the accumulated water to the soil in just the amounts necessary to keep the soil at the proper degree of moistness; the preservation of the pottery by keeping the moisture, ordinarily retained throughout the bottom of the tray, in the felt pad immediately below the aperture in the flowerpot; and the provision of means of ventilation of the saucer both at the top, i. e. the interior, and 45 at the bottom, i. e. the exterior thereof. This latter effect is secured by the provision of the ribs hereinabove described.

While I have described the preferred embodiment of my invention with some particularity, especially in connection with the size, configuration and disposition of the various ribs, utilized in the structure, it is obvious that various changes therein may be made without departing from my invention.

55 I claim:

1. A flowerpot saucer or tray comprising a cupped dish, the interior of the bottom of which is sunken at substantially the center of said dish, and a plurality of nearly, but not quite, radial elongated ribs extending along the lower surface of the bottom of the saucer and tapering in vertical thickness from their ends near the peripheral edge of the saucer toward the center thereof, the lower surfaces of said ribs being at 60 all times substantially in the same plane.

2. A flowerpot saucer or tray comprising a cupped dish, the bottom of which is sunken at substantially the center of said dish, a plurality of nearly, but not quite, radial elongated ribs 70 extending along the lower surface of the bottom of the saucer and tapering in vertical thickness from their ends near the peripheral edge of the saucer toward the center thereof, and a plurality of groups of short ribs disposed on the inner surface of the bottom of said saucer sub-

stantially above said elongated ribs, said short ribs being tapered in vertical thickness from their ends nearer the center of the saucer toward their opposite ends, the upper surfaces of said interior ribs and the lower surfaces of said exterior ribs being in substantially parallel planes. 5

3. A flowerpot saucer or tray comprising a cupped dish, the bottom of which is sunken at substantially the center of said dish, a plurality of nearly, but not quite, radial elongated ribs 10 extending along the lower surface of the bottom of the saucer and tapering in vertical thickness from their ends near the peripheral edge of the saucer toward the center thereof, and a plurality of groups of short ribs disposed on the 15 inner surface of the bottom of said saucer substantially above said elongated ribs, said short ribs being disposed at an angle to the long ribs and increasing in length from the center of the cup towards its peripheral edge and being tapered in vertical thickness from their ends nearer the center of the saucer toward their opposite ends, the upper surfaces of said interior ribs and the lower surfaces of said exterior ribs being in substantially parallel planes. 20

4. A flowerpot saucer or tray comprising a cupped dish, the bottom of which is sunken at substantially the center of said dish, a plurality of substantially radial elongated ribs extending from the lower surface of the bottom of the 30 saucer, and tapering in vertical thickness from their ends near the peripheral edge of the saucer toward the center thereof, and a pad of absorbent material positioned at such sunken center of the dish so as to constitute a reservoir 35 for water and effective to deliver moisture to the soil of a flowerpot placed into the saucer, the upper surfaces of said interior ribs and the lower surfaces of said exterior ribs being in substantially parallel planes. 40

5. A flowerpot saucer or tray comprising a cupped dish, the bottom of which is sunken at substantially the center of said dish, a plurality of substantially radial elongated ribs extending from the lower surface of the bottom of the 45 saucer, and tapering in vertical thickness from their ends near the peripheral edge of the saucer toward the center thereof, a plurality of groups of short ribs disposed on the inner surface of the bottom of said saucer substantially above said 50 elongated ribs, said short ribs increasing in length from the center of the saucer towards its peripheral edge and tapering in vertical thickness from their ends nearer the center of the saucer toward their opposite ends and a pad 55 of absorbent material positioned at such sunken center of the dish so as to constitute a reservoir for water and effective to deliver moisture to the soil of a flowerpot placed into the saucer, the upper surfaces of said interior ribs and the lower surfaces of said exterior ribs being in substantially parallel planes. 60

6. A flowerpot saucer or tray comprising a cupped element of molded rubber, the bottom of which is sunken at substantially the center thereof, a plurality of substantially, but not quite, radial elongated ribs integrally formed with said saucer and extending from the lower surface of the bottom of the saucer, said ribs tapering in vertical thickness from their ends 65 near the peripheral edge of the saucer toward the center thereof, a plurality of groups of short ribs integrally formed with said saucer and disposed on the inner surface of the bottom of said saucer, substantially above said elongated ribs, said 70 75

short ribs being disposed at an angle to the long ribs and increasing in length from the center of the saucer towards its peripheral edge, said short ribs being tapered in vertical thickness from 5 their ends nearer the center of the saucer toward their opposite ends, the upper surfaces of said interior ribs and the lower surfaces of said exterior ribs being in substantially parallel planes.

10 7. A flowerpot saucer or tray comprising a cupped dish of molded rubber, the bottom of which is sunken at substantially the center of said dish, a plurality of substantially, but not quite, radial elongated ribs integrally formed with 10 said dish and extending from the lower surface of the bottom of the dish, said ribs tapering in vertical thickness from their ends near the peripheral edge of the saucer toward the center thereof, said dish being capable of resting on a plane surface, the lower surfaces of said ribs, in 15 contact with said plane surface, lying substantially in one plane, a plurality of groups of short ribs integrally formed with said dish and disposed on the inner surface of the bottom of said dish substantially above said elongated ribs, said 20 short ribs being disposed at an angle to the long ribs, increasing in length from the center of the cup towards its peripheral edge, and tapering in vertical thickness from their ends nearer the center of the dish toward their opposite ends, 25 said short ribs being adapted to hold a flowerpot with a substantially flat bottom, the upper surfaces of said short ribs in contact with said flowerpot bottom lying substantially in one plane.

flowerpot placed into the saucer, the upper surfaces of said interior ribs and the lower surfaces of said exterior ribs being in substantially parallel planes.

8. A flowerpot saucer or tray comprising a cupped dish of molded rubber, the bottom of which is sunken at substantially the center of said dish, a plurality of substantially, but not quite radial elongated ribs integrally formed with 5 said dish and extending from the lower surface of the bottom of the dish, said ribs tapering in vertical thickness from their ends near the peripheral edge of the saucer toward the center thereof, said dish being capable of resting on a plane surface, the lower surfaces of said ribs, in 10 contact with said plane surface, lying substantially in one plane, a plurality of groups of short ribs integrally formed with said dish and disposed on the inner surface of the bottom of said dish substantially above said elongated ribs, said 15 short ribs being disposed at an angle to the long ribs, increasing in length from the center of the cup towards its peripheral edge, and tapering in vertical thickness from their ends nearer the center of the dish toward their opposite ends, 20 said short ribs being adapted to hold a flowerpot with a substantially flat bottom, the upper surfaces of said short ribs in contact with said flowerpot bottom lying substantially in one plane.
